(57) **CLAIM**

The ornamental design for a pocket hole clamp, as shown and described.

DESCRIPTION

FIG. 1 is an isometric view of the pocket hole clamp;
FIG. 2 is a side view thereof, as taken from the right side in FIG. 1;
FIG. 3 is a side view thereof, as taken from the left side in FIG. 1;
FIG. 4 is a front end view thereof (from the right as seen in FIG. 1);
FIG. 5 is a rear end view thereof (from the left as seen in FIG. 1);
FIG. 6 is a top view thereof; and,
FIG. 7 is a bottom view thereof.
The features shown in broken lines in the drawing figures depict environmental subject matter only and form no part of the claimed design.
